CLAIM

The ornamental design for an insulated tray, substantially as shown and described.

DESCRIPTION

FIG. 1 is a perspective view of an insulated tray therefor showing my new design;

FIG. 2 is an enlarged top plan view;

FIG. 3 is a side elevational view thereof;

FIG. 4 is an end elevational view thereof; and

FIG. 5 is a bottom plan view thereof.

FIG. 1.FIG. 2.FIG. 3.FIG. 4.FIG. 5.
